(57) **CLAIM**

The ornamental design for a multiple function shank for a nut driver, as shown and described.

DESCRIPTION

FIG. 1 is a perspective view of my multiple function shank for a nut driver showing my new design;

FIG. 2 is a top plan view thereof;

FIG. 3 is a bottom plan view thereof;

FIG. 4 is a front elevation view thereof;

FIG. 5 is a left side elevation view thereof;

FIG. 6 is a rear elevation view thereof;

FIG. 7 is a right side elevation view thereof; and,

FIG. 8 is a perspective view thereof.

The broken line showing of handle in FIG. 8 is included for the purpose of illustrating environmental structure and forms no part of the claimed design.

UNITED STATES PATENT AND TRADEMARK OFFICE
CERTIFICATE OF CORRECTION

PATENT NO. : D615,832 S
APPLICATION NO. : 29/314645
DATED : May 18, 2010
INVENTOR(S) : Frank R. Patti

Page 1 of 7

It is certified that error appears in the above-identified patent and that said Letters Patent is hereby corrected as shown below:

The title page showing the illustrative figure should be deleted to be replaced with the attached title page.

The drawing sheets, consisting of Figs. 1-8, should be deleted to be replaced with the drawing sheets, consisting of Figs. 1-8, as shown on the attached page.

In the drawings:

1. Fig. 1 has been corrected by making the diameter of the shank even from the top end of the shank to the bottom end of the shank, and consistent with all the other Figs. in the patent. Further, the diameter of the socket at the top end of the shank has been made even from the right end of the socket to the left end of the socket, and consistent with all the other Figs. in the patent. Lastly, the liner shade lines on the socket at the top end of the shank have been straightened and properly spaced apart.
2. Fig. 2 has been corrected by lengthening the rectangle to be consistent with the same part as shown in Figs. 5 and 7. Further, the liner shade lines on the right side of the rectangle have been properly spaced apart.
3. Fig. 3 has been corrected by lengthening the rectangle to be consistent with the same part as shown in Figs. 5 and 7, and corrected Fig. 2. Further, the large circle has been made round. Lastly, the liner shade lines on the right side of the rectangle have been properly spaced apart.
4. Fig. 4 has been corrected by changing the orientation of the hexagon at the top end of the shank to be consistent with the same hexagon as shown in Figs. 1 and 8. Said hexagon has been rotated 1/8 of a turn. Further the liner shade lines on the right side of the shank have been properly spaced apart.

Signed and Sealed this
Twenty-second Day of February, 2011

David J. Kappos
Director of the United States Patent and Trademark Office

CERTIFICATE OF CORRECTION (continued)
U.S. Pat. No. D615,832 S

Page 2 of 7

In the drawings:

5. Fig. 5 has been corrected by properly spacing the linier shade lines at the top of the rectangle at the top end of the shank. Further, the linier shade lines on the left side of the shank have also been properly spaced apart.

6. Fig. 6 has been corrected by changing the orientation of the hexagon at the top end of the shank to be consistent with the same hexagon as shown Figs. 1 and 8, and corrected Fig. 4. Said hexagon has been rotated 1/8 of a turn. Lastly, the linier shade lines on the right side of the shank have been properly spaced apart.

7. Fig. 7 has been corrected by properly spacing the linier shade lines at the top of the rectangle at the top end of the shank.

8. Fig. 8 has been corrected by making the diameter of the socket at the top end of the shank even from the right end of the socket to the left end of the socket. Further, the linier shade lines on the socket at the top end of the shank have been straightened and properly spaced apart. Further, the originally filed smaller unclaimed handle has been put back on the claimed design. Further, the broken arc line of the unclaimed handle that is shown behind the shank has been removed. Further, a break has been added to the arc line of the unclaimed handle that is shown on the shank. Lastly, the broken lines of the unclaimed handle that intrude upon the linier shade lines of the shank have been removed.
